Victor J. Evans

ATTORNEY

UNITED STATES PATENT OFFICE.

JOHN ENDRESON, OF BROOKLYN, NEW YORK.

POCKET-FILTER.

1,292,737.

Specification of Letters Patent. Patented Jan. 28, 1919.

Application filed April 12, 1918. Serial No. 228,250.

To all whom it may concern:

Be it known that I, JOHN ENDRESON, a citizen of the United States, residing at Brooklyn, in the county of Kings and State 5 of New York, have invented new and useful Improvements in Pocket-Filters, of which the following is a specification.

This invention relates to pocket filters and has for its object the provision of a device 10 of this character which will include instrumentalities whereby the same can be conveniently carried in the pocket of the user; designing and arranging said instrumentalities so that the fluid will be thoroughly 15 cleansed and relieved of all dangerous germs and impurities in the passage of the fluid toward the outlet of the device; providing means in the device whereby a column of water may be always maintained therein as 20 long as the intake end of the device is projected into a body of water, and further associating mating parts of the device so that they may be conveniently disconnected from each other to fully expose the filtering sub- 25 stance and permit of removal thereof when desired.

With the above and other objects in view which will appear as the nature of the invention is better understood, the same consists 30 in the improved construction and novel arrangements of parts which will herein-after be fully described and particularly pointed out in the claim.

In the accompanying drawings, has been 35 illustrated, a single and preferred form of the invention, it being, however, understood that no limitations are necessarily made to the precise structural details therein exhibited, but that changes, alterations and modifications within the scope of the claim may be resorted to when desired.

Figure 1 is a side view of the device with the cap applied.

Fig. 2 is a vertical section therethrough 45 with the cap removed.

Fig. 3 is a section on line 3—3 of Fig. 2.

The device comprises an intermediate filtering chamber 5 which preferably consists of a single length of metal or rigid tubing, 50 the same being exteriorly threaded at 6 and interiorly threaded at 7 at its opposite ends respectively. Connected with the threads 7 is a mouth piece 8 having a thread 9 adapted to receive a corresponding internal thread 55 10 on a closing and protecting cap 11 as illustrated in Fig. 1.

The opposite thread 6 of the tubular chamber 5 is connected with a valve chamber 12 the same also being of tubular formation and it is provided with an internal valve seat 60 13 above which is a ball valve 14. Below the seat is a disk or wire cloth or filtering substance 15, while directly under the latter and detachably connected with the tubular chamber 12 is a strainer 16. Within the 65 valve chamber at a point above the ball 14 is a filtering disk 17 of wire gauze and above the latter is a disk 18 of suitable filtering cloth. The disk 15 is arranged to rest against the base of the valve seat and the strainer 70 serves as a retainer to hold said disk in proper position so that the water as it passes from the strainer and into the valve chamber will be intercepted by said disk and strained. The disks 17 and 18 are preferably remov- 75 ably mounted against a shoulder 19 arranged within the valve chamber.

At the opposite end of the filtering chamber at a point directly beneath the mouth piece 8 is a filtering disk 20 of wire gauze 80 and arranged thereabove is a second disk 21 of suitable fibrous material, such as linen. The disk 18 may also be constructed of linen. A shoulder 22 within the upper end of the filtering chamber is designed to receive the 85 disks 20 and 21 thereagainst.

Within the filtering chamber are closely associated long fibrous strands 23 of porous material such as linen threads. These strands are arranged to almost entirely occupy the filtering chamber. Each strand is of circular formation in transverse section so that infinitesimal longitudinal spaces 24 are formed between the respective strands. Through this arrangement it will be manifest 90 that a free passage is provided for the water in its course through the filtering chamber and yet it will be properly subjected to the action of the strands 23 so that all injurious impurities will be properly removed before the water reaches the mouth piece 8.

By providing the valve 14 it will be observed that as soon as water is drawn into the device and suction removed from the 105 mouth piece, the ball will gravitate to a closed position and a column of water will therefore be maintained in the device so that without undue exertion of suction subsequently against the mouth piece the water 110 can be taken up in a perfectly free manner as the column thus preserved will be main-

tained in direct contact with the source from which the water is taken.

The device is designed to be carried in the pocket of the user, it will be found extremely valuable to travelers and those desiring to partake of water which might not be in a sanitary condition and the several features of the device as specified herein permit the user to take of such waters with a certain 10 measure of safety.

What is claimed as new is:—

A filter comprising a filtering chamber having an outlet and by means of which

liquid may be drawn through said chamber, a filling of filtering substance associated with 15 said chamber, and a valve chamber detachably connected with said filter chamber, a seat in said valve chamber, a filtering disk beneath said seat, an intake strainer leading to said seat, and a gravity valve co-acting 20 with said seat and serving to maintain a column of liquid in the filter and valve chambers respectively when suction upon said outlet end is broken.

In testimony whereof I affix my signature. 25
JOHN ENDRESON.
